UNITED STATES PATENT OFFICE.

DUNCAN DUNBAR WRIGHT, OF ARTHURETTE, NEW BRUNSWICK, CANADA.

RAIL-JOINT.

No. 894,712.

Specification of Letters Patent.

Patented July 28, 1908.

Application filed July 2, 1907. Serial No. 381,824.

To all whom it may concern:

Be it known that I, DUNCAN DUNBAR WRIGHT, a subject of the King of Great Britain, residing at Arthurette, in the Province of New Brunswick and Dominion of Canada, have invented new and useful Improvements in Rail-Joints, of which the following is a specification.

This invention relates to railroad track construction and more particularly to rail joints of that type in which the abutting ends of the rail sections are designed to overlap and are fastened together in any suitable manner.

15 The invention has for one of its objects to improve and simplify the construction of devices of this character, so as to produce a strong and durable rail joint, whereby the rails shall be maintained in perfect alignment, sagging prevented and noise and pounding eliminated as the wheels of a train pass over the joint.

20 A further object of the invention is the provision of a rail joint composed of meeting ends of the adjacent rails which are halved so as to overlap, and the overlapping portions having one or more projections adapted to engage in openings of the other portion which together with fastening bolts serve to 25 hold the rails securely together and in alignment, there being no necessity for fish plates.

Another object of the invention is to so 30 construct the tread surfaces of the rail sections that the car wheels can pass over the space between the meeting ends of the sections without noise or shock.

35 With these objects in view and others, as will appear as the description proceeds, the invention consists in the various novel features of construction and arrangement of parts, which will be more fully described and set forth with particularity in the appended claims.

40 In the accompanying drawing, which illustrates one of the embodiments of the invention:—Figure 1 is a side view of a rail joint. Fig. 2 is a plan view. Fig. 3 is a transverse section on the line 3—3. Figs. 4 and 5 are transverse sections on lines 4—4 and 5—5 of 45 Fig. 1.

50 Similar reference characters are employed to designate like characters in the several views.

55 Referring to the drawing, A and B designate the meeting ends of two rail sections which latter may be of standard construc-

tion except at the meeting ends where they are halved, so as to overlap. The end of each section is cut away on a center line, as indicated at 1 in Fig. 2, thereby forming a shoulder 2 and the halved portion of one section is presented to that of the other section so that a substantially uniform rail is produced. On the halved portions 3 and 4 are projections or lugs 5 projecting laterally from the central vertical surface 1, the projection or projections of one section entering an opening or openings 6 of the other section. The overlapping portions 3 and 4 of the rails have transverse bolt receiving apertures 7 for the bolts 8, whereby the rail sections are secured together. Preferably three bolts are employed at the middle of the rail joint and two at each end.

50 The tread of each rail section is cut away at the shoulder 2 and also at the extremity of each halved portion, as indicated by 9, in Fig. 1 and a portion of the tread opposite the shoulder 2 is raised as indicated at 10, so that the car wheels will pass from one rail section 55 to the other without coming in contact with the meeting end surfaces of the sections. As shown in Fig. 1, the extremity of each rail section is provided with a tongue 11 that engages between the head 12 and base 13 of the adjacent section and these tongues coöperate with the projections 5 to prevent relative vertical displacement as the car wheels pass from one rail section to the other.

60 From the foregoing description, taken in connection with the accompanying drawing, the advantages of the construction and method of operation will be readily apparent to those skilled in the art to which the invention appertains, and while I have described 65 the principle of operation of the invention together with the device which I now consider to be the best embodiment of the invention I desire to have it understood that the device shown is merely illustrative and that 70 such changes may be made when desired as are within the scope of the claims.

Having thus described the invention, what is claimed, is:—

75 1. A rail joint comprising a pair of rails 70 having halved extremities arranged to overlap, projections formed integrally with the said extremities and arranged to engage in openings in the latter, groups of bolts passing through the rail sections and disposed at opposite sides of the projections for securing the rail sections together, and tongues pro-

jecting from the said extremities adapted to engage between and bear on the heads and bases of the rail sections.

2. A rail joint comprising a pair of rail sections halved at their ends and arranged in overlapping relation to form a continuous rail, the tread surface of the rail being depressed at the end surfaces of the sections and elevated at a point opposite of the de-

pressed portions, and means for connecting the rail sections together.

In testimony whereof, I affix my signature in presence of two witnesses.

DUNCAN DUNBAR WRIGHT.
